(No Model.)

B. E. BOYDEN.

BANJO.

No. 449,200.

Patented Mar. 31, 1891.

UNITED STATES PATENT OFFICE.

BYRON E. BOYDEN, OF BRIDGEPORT, CONNECTICUT.

BANJO.

SPECIFICATION forming part of Letters Patent No. 449,200, dated March 31, 1891.

Application filed August 14, 1890. Serial No. 361,950. (No model.)

To all whom it may concern:

Be it known that I, BYRON E. BOYDEN, a citizen of the United States, residing at Bridgeport, in the county of Fairfield and State of Connecticut, have invented certain new and useful Improvements in Banjos; and I do hereby declare the following to be a full, clear, and exact description of the invention, such as will enable others skilled in the art to which it appertains to make and use the same.

My invention has for its object to increase the richness and fullness of tone and to strengthen and prolong the tones of banjos—in other words, to modify the sharp staccato quality of the tone, giving instead tones of greater volume and resonance, and to generally improve the details of construction.

With these ends in view I have devised the novel banjo of which the following description, in connection with the accompanying drawings, is a specification, numerals being used to designate the several parts.

Figure 1 is a plan view of the head of a banjo, a portion of the head being broken away and the holding-ring shown in section; Fig. 2, a section on the line *xx* in Fig. 1, looking toward the right, the staff being removed; Fig. 3, a vertical longitudinal section of the head-block; Fig. 4, a section of one of the tubes having a clamping-lug, and Fig. 5 a section of one of the ordinary tubes.

1 denotes the staff; 4, the head, made, as usual, of sheep-skin or parchment, and 5 the usual wire about which the outer edge of the head is wrapped.

The head of my novel banjo is stretched over a holding-ring 2 by a tightening-ring 6. The holding-ring is provided with a downwardly-extending flange 3, and at its outer edge with a rounded bearing-surface 19, the top of the ring inclining downward and inward from the bearing-surface, leaving a space 20 between the head and ring, as will be more fully explained. The tightening-ring is of just sufficient size to receive the holding-ring and head within it and to rest upon the wire, as is clearly shown in Fig. 2. The rim consists of a series of metallic tubes, (denoted by 7,) which are held together by bands 9. These tubes are closed at the bottom, as shown in Figs. 4 and 5, and are provided on their inner sides with sound-open-

ings 10. In practice a portion of the tubes—for example, every third or fourth tube—are provided with lugs 8, (see Fig. 4,) the purpose of which will presently be explained. These tubes may either be drawn or cast. In practice I have used for the ordinary tubes shells drawn from disks of sheet metal, and have cast the tubes provided with lugs, the lugs and tubes being cast integral, although these are mere details of construction and do not affect the principle of my invention in the slightest. Any suitable bands may be used to hold the tubes in place, although in practice I preferably use wires and provide openings 11 in the opposite sides of the tubes, through which the wires are passed.

In order to provide simple means for connecting the ends of the wires and holding the tubes closely and firmly together in a circular arrangement, as shown, and at the same time to give a firm support for the staff, I use a head-block 12, which is cast in a single piece, the inner and outer sides being preferably formed in imitation of the tubes, so as to give a neat and uniform appearance to the exterior of the banjo. This head-block is provided with a central opening 13, which receives the end of the staff, with longitudinal openings 14, which receive the ends of the wires, the latter being threaded, as shown, and with recesses 15 to receive nuts 16, which engage the threaded ends of the wires, as is clearly shown in Fig. 3. It will be seen that by turning these nuts the ends of the wires may be drawn toward each other, which will hold the tubes closely in contact with each other and prevent the slightest movement in use.

The head is tightened by means of hooked bolts 17, the hooked ends of which engage the tightening-ring and the threaded lower ends of which pass through openings in lugs 8, as clearly shown in Figs. 2 and 4. The bolts are drawn downward, which draws the tightening-ring downward and stretches the head over the holding-ring by simply tightening the nuts 18 on the hooked bolts. This is an important feature, as heretofore the tightening-lugs have been secured to wooden or metallic rims by bolts or screws passing through the rims. This I wholly avoid, which lessens the cost of production and greatly improves

the appearance of the instrument. In assembling, flange 3 upon the holding-ring passes within the upper ends of the tubes, the ring being provided with sound-openings 5 21, which register with the tubes and extend into space 20 under the head. (See Fig. 2.)

When the wires which hold the tubes are tightened up, as already explained, it will be apparent that the tubes are drawn inward 10 20 against this flange, thus giving to the instrument ample strength to resist any possible strain that can be brought to bear upon it.

Having thus described my invention, I claim—

15 1. In a banjo, a rim consisting of a series of metallic tubes held together by suitable bands and provided with sound-openings on their inner sides.

20 2. In a banjo, a rim consisting of a series of metallic tubes held in position by bands passed through openings in the tubes, said tubes being closed at their lower ends and provided with sound-openings on their inner sides.

25 3. In a banjo, a rim consisting of a series of metallic tubes, bands threaded at their ends by which said tubes are held in position, a head-block having longitudinal openings to receive the ends of the bands and transverse 30 openings to receive nuts which engage the threaded ends of the bands, substantially as described.

4. In a banjo, a series of metallic tubes, bands by which they are held together and 35 which are threaded at their ends, in combination with a staff and a head-block having an opening to receive the staff, openings to receive the ends of the bands, and other openings to receive nuts which engage the ends of 40 the bands, substantially as described.

5. In a banjo, a rim consisting of a series of metallic tubes, a portion of which are pro-

vided with lugs 8, in combination with a head, a tightening-ring by which the head is stretched, and hooked bolts which engage the 45 tightening-ring and the threaded lower ends of which engage the lugs, substantially as described.

6. The combination, with the tubes, the holding-ring having a flange resting within the tubes, and bands by which the tubes are held together, of a head-block having openings to receive the ends of the bands, and nuts engaging the ends of the bands and acting to draw the tubes together and against the 50 flange.

7. The combination, with the tubes, some of which are provided with lugs, the holding-ring resting within the tubes and having sound-openings registering with the tubes, 60 and means, substantially as described and shown, for holding the tubes together, of a head, a tightening-ring, hooked bolts engaging the tightening-ring and passing through the lugs, and nuts upon said bolts, whereby 65 the head is tightened.

8. In a banjo, a holding-ring for the head, having a rounded bearing-surface at its outer edge and sound-openings through it, the top of the ring inclining downward and inward 70 from the bearing-surface, so as to leave a space between the ring and head, substantially as described.

9. In a banjo, the combination, with the head and tightening-ring, of a rim consisting 75 of metallic tubes, some of which are provided with lugs 8, and hooked bolts engaging the tightening-ring and the lugs.

In testimony whereof I affix my signature in presence of two witnesses.

BYRON E. BOYDEN.
